CLAIM

The ornamental design for a jewel setting, as shown and described.

DESCRIPTION

FIG. 1 is front right top perspective view of a jewel setting showing my new design.

FIG. 2 is a front left top perspective view thereof.

FIG. 3 is a bottom rear perspective view thereof at a first angle.

FIG. 4 is a front elevation view thereof.

FIG. 5 is a rear elevation view thereof.

FIG. 6 is a right side elevation view thereof.

FIG. 7 is a left side elevation view thereof.

FIG. 8 is top plan view thereof; and,

FIG. 9 is a bottom plan view thereof.

The dash-dash lines represent portions of the jewel setting that form no part of the claimed design. The dash-dot lines represent the bounds of the claimed design and form no part thereof.

1 Claim, 9 Drawing Sheets(56)
